Primary Examiner — John Windmuller(74) *Attorney, Agent, or Firm* — Claus Eight IPS; Michael Catania(57) **CLAIM**

The ornamental design for an antenna, as shown and described.

DESCRIPTION

FIG. 1 is a top plan view of an antenna on a base in broken lines;

FIG. 2 is a side elevation view thereof;

FIG. 3 is a bottom plan view thereof;

FIG. 4 is a top plan view of the antenna without a base; and, FIG. 5 is a side elevation view thereof.

The broken line showing of a base represents environment only and forms no part of the claimed design.

1 Claim, 2 Drawing Sheets
